UNITED STATES PATENT OFFICE.

HENRY SCHOOLBERG, OF PITTSBURGH, PENNSYLVANIA.

VISIBLE LOOSE-LEAF INDEX AND RECORD.

Application filed November 30, 1926. Serial No. 151,621.

My invention relates to a new and improved visible index and recording book or device, and more particularly to means of the character stated including a loose-leaf post-type 5 binder.

Among the objects of the present invention are, to provide a leaf or sheet having a visible index, a record space, and means for securing the sheet or a number of the sheets within a 10 loose-leaf binder; sheets of such character that they may differ in size and still be used in the same binder, thereby providing sheets in the same book having recording spaces differing in size and capable of being arranged 15 to provide a visible alphabetical index; to provide sheets and means whereby new sheets may be added, having the visible index of the added sheets placed in the desired positions and in an alphabetical order, without interference with or the removal of previously inserted sheets; to provide mechanical means 20 for positioning the sheets within the binder; and the provision of a sheet of the character specified permitting the sheet to be used on 25 each face and positioned with the index thereof arranged in a visible alphabetical order relative to the other sheets.

In the accompanying drawings, which illustrate an application of my invention;

30 Fig. 1 is a plan view showing a loose-leaf binder in open position in connection with a number of recording sheets constructed in accordance with my invention applied thereto, together with means for positioning the 35 sheets within the binder;

Fig. 2, a detail plan view showing a recording sheet;

Fig. 3, a perspective view showing a portion of the sheet-positioning means; and

40 Fig. 4, a plan view showing a plurality of record sheets assembled.

Referring to the drawings, 5 and 6 respectively designate the top and bottom covers of a loose-leaf binder, and 7, sectional posts employed for securing the said covers together. This construction is of the well-known type of sectional post binders; the locking means cooperating with the posts for locking the top and bottom covers against separation, 50 however, is not shown in the drawings.

In addition to the posts 7, the binder is provided with a post 8 designed to connect a sheet-inserting or positioning means designated generally by the numeral 9, to be hereinafter fully described.

A characteristic and important feature of my invention resides in the combined visible index and record sheets employed by me. These sheets 10 or 10', as illustrated and as preferred, include a main data-recording 60 space *a*, and detachable visible marginal portions comprising a plurality of detachable strips 11 and 12 arranged respectively at the tops and bottoms of the sheets. The said strips are designed to have index data printed or otherwise displayed thereon, for example, the names of clients or customers or other index matter.

When the loose-leaf sheets 10 are assembled for use, the index portions thereof will 70 present a visible alphabetical index, see Fig. 4. In the drawings, I have shown only three detachable index strips arranged at the tops and bottoms of the sheets, but more may be provided on each sheet if desired. The strips 75 are preferably formed by perforating the sheet material and may be readily torn off from the sheet, as required.

Each index and record recording sheet is 80 provided with means for securing the sheet to the posts of the binder; these means, as shown, comprise projections or tab portions 13 located at the upper end and at the side of each sheet. Each of the extended portions 13 is provided with post-engaging slots or 85 notches 14, and with a series of openings 15.

It will be understood that, by means of the notches 14, the portion 13 may be attached to the binder posts by passing the sheet into the desired position relative to the posts, and then 90 pressing the notched portions 13 against the posts sufficiently to cause the notches 14 thereof to encircle the posts. By means of the sheet-attaching extended portions 13, the sheets may be applied either to one or both 95 faces of the binder covers, and similar sheets may be used for either face.

The mechanical means 9, constructed of thin spring metal, for inserting and positioning one or a number of sheets in the desired 100 position in the binder, includes a slotted arm or link 16 having an apertured head 17, the latter being adapted to be pivotally mounted on the post 8; and a second link or arm 18 engaging the slotted arm 16 in such a manner 105 as to have a free sliding engagement therewith. One end of the arm 18 is secured to a movable plate member 19 by means of a screw 20 in such manner as to allow movement of member 19 relatively to the arm 18. The 110

prime object of links 16 and 18 is to secure the sheet inserter means to the loose-leaf binder.

Plate member 19 is provided with a series of vertically extending posts or pins 21 arranged so that the distance between each post will correspond to the distance between the holes 15 in the extended portions 13 of the sheet. The sheet-positioning means, in addition to the parts just described, include a flat strip member 22 pivotally secured to the plate 19 by means of a screw 23.

The manner of using the sheet-shifting means is particularly shown in Fig. 1. In this figure, the means 9 are shown in connection with a plurality of sheets designed to be moved from one position to another for the purpose of providing a space to contain the new sheet or sheets, and particularly the index portions of the newly-inserted sheets.

The operation of changing the position of a sheet or a series of sheets by means of the device 9 may be performed by first securing the sheets to be shifted to the sheet-positioning means 9. This is accomplished by placing the openings 15 of portions 13 over pins 21, and moving the member 22 over the sheets and the plate member 19. It will be seen that the sheets to be shifted are now securely attached to the shifting device 9, and the latter may, owing to its linkage connection with the post 8, be moved into the desired positions for moving the sheets and the indexes thereof into the space desired.

After the sheets are placed in their new position, the pins 21 are freed from the openings 15, and the positioning means swung free of the sheets and removed from the binder; or, the positioning means may be moved into a position, while still secured to the binder, in which it will not interfere with the inserted sheets.

It will be seen that a sheet or a number of sheets may be inserted, removed, or shifted without the necessity of opening the binder or separating the covers thereof.

Spacing pages 25 having indicating characters are employed to separate one series of the combined visible alphabetical index and recording sheets from another similar series.

What I claim is:

1. The combination with a loose-leaf binder, of a sheet having a marginal projection on its binding edge shorter in length than the binding edge of the sheet from which it projects and shorter in length than the binding edge of the binder.

2. The combination with a loose-leaf binder, of a sheet having a marginal projection on its binding edge shorter in length than the binding edge of the sheet from which it

projects and shorter in length than the binding edge of the binder, said projection having a plurality of closely spaced alined openings.

3. A series of loose leaves adapted for insertion in a binder overlapping each other providing visible index portions, said visible index portions each including a detachable index strip whereby when the index strip is detached the corresponding area of an alined sheet underneath becomes visible.

4. A series of loose leaves adapted for insertion in a binder overlapping each other providing visible index portions said visible index portions each including a plurality of detachable index strips whereby when one or more index strips are detached the corresponding area of an alined sheet underneath becomes visible.

5. A series of sheets each adapted to be held by one of its edges in a binder and provided with a detachable index strip adjacent to a non-binding edge whereby when said strip is detached the corresponding area of another alined sheet underneath becomes visible.

6. A series of sheets each adapted to be held by one of its edges in a binder and provided with a plurality of detachable index strips adjacent to a non-binding edge whereby when one or more of said strips are detached the corresponding area of another alined sheet underneath becomes visible.

7. A series of sheets for a binder each sheet having a detachable index strip parallel and adjacent to a non-binding edge of the sheet whereby when the index strip is detached the corresponding area of another alined sheet underneath becomes visible.

8. A series of sheets for a binder each sheet having a plurality of detachable index strips parallel and adjacent to a non-binding edge of the sheet whereby when one or more index strips are detached the corresponding area of another alined sheet underneath becomes visible.

9. A series of sheets for a binder each sheet having a detachable index strip adjacent to an edge and perpendicular to the binding edge whereby when the index strip is detached the corresponding area of an alined sheet underneath becomes visible.

10. A series of sheets for a binder each sheet having a plurality of detachable index strips adjacent to an edge and perpendicular to the binding edge whereby one or more index strips are detached the corresponding area of an alined sheet underneath becomes visible.

In testimony whereof I affix my signature.

HENRY SCHOOLBERG.
